J. P. WHITMORE,
APPARATUS FOR MAKING PAINTED WINDOW SHADE MATERIAL.
APPLICATION FILED FEB. 13, 1920.

1,407,241.

Patented Feb. 21, 1922.

Inventor:

John P. Whitmore

24 Arthur P. Knight
Atty

UNITED STATES PATENT OFFICE.

JOHN P. WHITMORE, OF SOUTH PASADENA, CALIFORNIA.

APPARATUS FOR MAKING PAINTED WINDOW-SHADE MATERIAL.

1,407,241.

Specification of Letters Patent. Patented Feb. 21, 1922.

Application filed February 13, 1920. Serial No. 358,458.

To all whom it may concern:

Be it known that I, JOHN P. WHITMORE, a citizen of the United States, residing at South Pasadena, in the county of Los Angeles and State of California, have invented new and useful Improvements in Apparatus for Making Painted Window-Shade Material, of which the following is a specification.

10 This invention relates to improvements in apparatus for applying opaque paint to paper so as to produce shade material such as disclosed in Patent No. 1,322,855, granted to me November 25th, 1919, and the main 15 object of the present invention is to provide for improved distribution of the paint on the shade material, and for more effective control of the feeding of the shade material.

20 The accompanying drawings illustrate an embodiment of my invention, and referring thereto:

Fig. 1 is a vertical section of the apparatus;

25 Fig. 2 is an enlarged elevation of the doctor devices;

Fig. 3 is a detail elevation of the slip drive means for winding up the parting strips;

30 Fig. 4 is a cross-section of the finished shade material.

The apparatus shown in the drawing comprises means 1 for rotatably supporting a roll α of paper suitable for forming the body 35 of the shade material, guide rollers 2, 3, 4 and 5 over which said paper is guided from said roll into a tank 6 containing a suitable paint, and means for drawing the paper from said tank and maintaining it 40 exposed to the air and under suitable tension in such manner as to ensure drying of the paint and delivery of the paper in a smooth uniform roll. For this purpose I prefer to provide a drying tower 7 extending 45 above paint tank 6 and having a feed roller 8 in its upper portion, over which the paper sheet or strip b passes, said strip passing under a roller 9 immersed in tank 6 and then upwardly through a vertical casing 10 and over roller 8, and then down to a suitable winding up roller or drum 11. The height of tower 7 should be sufficient to permit the paper to become substantially dry by the time it reaches the roller 11. To assist 50 in such drying operation, a draft or current of air may be maintained in casing 10 by blower 12, having nozzles 13 discharging air upwardly on each side of the strip b of paper. Suitable means, such as doctor strips or blades 14 and 15, are provided for removing excess paint from the paper sheet, said means extending on opposite sides of the sheet directly above tank 6 and being offset or arranged at different levels and extending in different horizontal planes in such 60 manner so as to slightly overlap and produce a tension on the sheet. The outer ends of the doctor blades are rounded or convex, as shown, so as to smoothly press and wipe the paint in distinction to scraping the 65 paint, this being very desirable when paper is used as the shade material. In the case of shade cloth, knife edged doctor blades are generally used, which scrape off the paint from the surface and cause the interstices to 70 be filled up even with the outer surface, but, as paper presents no interstices, it is not practicable to scrape off the paint in this manner and at the same time leave sufficient paint on the paper to give the desired finish. 75 This difficulty is overcome by having round edged doctor blades which wipe and smooth the paint without removing too much of it from the surface. Brushes 16 and 17 are provided above the doctor blades on opposite sides of sheet b to smooth off the coating of paint. Suitable means, such as motor 19, having driving connections 20 and 21, is provided for driving the feed roller 8, and said motor is also connected by driving 80 connection 21' to the roller 5 in such manner that rollers 5 and 8 feed the paper sheet at the same speed, thereby eliminating any undue strain on the paper after application of the paint thereto by reason of the tension 85 required to unwind the paper from the roll α and over the rolls 2, 3 and 4. By thus drawing the paper strip or sheet at uniform speed at a point before it enters the paint and at the upper part of the drying portion 90 of the sheet, I avoid uneven stretching and straining of the paper. Motor 19 is also connected by pulley and belt connections 95 46 to a shaft 48 operating a variable speed mechanism for driving the wind up roller 100 11 at such speed as to keep the shade material slack after it passes the feed roller 8 but prevent it from sagging to the floor. For this purpose shaft 48 may carry a friction disk 49 engaged by a friction roller 50 105 splined to a shaft 51 and movable along the shaft 51 by means of a controlling lever 52,

manually operated to vary the distance of roller 50 from the center of the disk 49 and to thereby vary the speed of shaft 51 and of the roller 11 connected to said shaft by 5 gearing 53.

In order to enable the feed roller 8 to feed the paper sheet *b* it is necessary to provide a presser roll or "nip" roll, indicated at 23, rotatably mounted, for example, 10 on a vertically swinging frame 26, so as to exert pressure on the paper *b* by the weight of said roller and frame, assisted, if necessary, by suitable spring means. I have found that there is a tendency for the paint 15 to "offset" or transfer from the paper *b* to the feed roller 8 at parts which are subjected to such pressure, and to prevent this I provide a "dead" sheet or parting strip 27 supplied from a roll 29 and passing between sheet *b* and roller 8 and a similar 20 parting strip 28 supplied from a roll 30 and passing between sheet *b* and "nip" roller 23, said sheets passing eventually to receiving means consisting of rolls 32 and 25 33 on which they are wound in condition for reuse. In order to wind the strips 27 and 28 on the rolls 32 and 33, the latter may be rotated through "slip-drive" connections from the shaft 8' of roller 8, for example, 30 as shown in Fig. 3, in the case of roller 32, by a belt 34 having tightener 34' and driven by a pulley 42 which is driven by belt connection 43 from a pulley 44 on the shaft of the roller 8. The parting strips 27 and 35 28 may be only as wide as the "nip" roller 25, which may extend over only the middle portion of the paper sheet *b* and feed roller 8.

In case the apparatus is used for making 40 paper shade material re-enforced at the edges, I may provide a tape feeding device at each edge of the sheet *b* comprising feed rollers 35 feeding gummed tape *c* from reels *d* to a moistening roller 36 from which 45 the tape passes into contact with the paper sheet *b* against which it is pressed by roller 37. If desired, a re-enforcing thread or filament *e* may be supplied from a reel *f*, and pass between sheet *b* and each of the 50 tapes *c*, being secured in position by the gum that holds the tape in place.

My process may be carried out in the above described apparatus as follows:

The paper sheet *b* is drawn from roll *a* 55 over guide rollers 2 to 5 and under roller 9 in tank 6, and then up through casing 10 and over feed roller 8 and then down to the winding up roll 11. In passing through tank 6 the sheet *b* becomes coated on both 60 sides with opaque paint, taken up from a body of paint indicated at *g* in said tank, the excess of paint being wiped off by the

doctor blades 14 and 15 and smoothed off by brushes 16 and 17. In passing up through casing 10 the paint becomes fairly 65 dry, and in passing over the feed roller 8 and between said roller and the "nip" roller 25, it is separated from said rollers by the "dead" sheets or parting strips 27 and 28, respectively, so that the paint does 70 not offset on to said rollers, and the coat of paint is maintained in smooth uniform condition. In case the re-enforcing tapes are to be applied to the shade material, said tapes are drawn along with said material, 75 after being moistened, and are pressed down on the shade material to adhere to same, the coating of paint being applied over said re-enforcing tapes in obvious manner. The re-enforcing threads *e* are applied at the 80 same time and are held in place by the gum that holds the paper tapes *c* in position.

By the above described operation, a finished shade material is produced such as is disclosed in my Letters Patent aforesaid, 85 and shown in partial section in Fig. 4.

What I claim is:

1. In an apparatus for painting shade material, the combination with means for supporting a roll of paper, a paint receptacle, 90 means for guiding the paper into said paint receptacle, a feed roller for drawing the paper from the paint receptacle mounted above the paint receptacle a sufficient distance to enable drying of the paint before 95 it passes said feed roller, a feed roller over which the paper is passed before it passes to the paint receptacle and means for operating said feed rollers at the same speed so as to avoid strain on the paper while the 100 paint is wet.

2. In an apparatus for painting shade material, a feed roller for drawing the painted shade material forward, a presser roller for pressing on the shade material to ensure 105 feeding thereof, means for supplying a parting strip between the shade material and one of the said rollers, and means for winding up the parting strip including a slip-drive to prevent undue strain on the parting 110 strip.

3. In an apparatus for painting shade material, a feed roller adapted to feed the painted shade material upwardly and then downwardly, and means for winding up the 115 painted shade material comprising a roller adapted to receive the shade material fed downwardly from the feed roller and provided with variable speed driving means.

In testimony whereof I have hereunto 120 subscribed my name this 4th day of February, 1920.

JOHN P. WHITMORE.
